UNITED STATES PATENT OFFICE.

WILLIAM A. FIRSTBROOK, OF TORONTO, CANADA.

LUMBER-JOINTING MACHINE.

SPECIFICATION forming part of Letters Patent No. 674,368, dated May 21, 1901.

Application filed July 9, 1900. Serial No. 22,944. (No model.)

To all whom it may concern.

Be it known that I, WILLIAM A. FIRSTBROOK, a subject of the Queen of Great Britain, residing at Toronto, in the Dominion of Canada, have invented certain new and useful Improvements in Machines for Jointing and Setting Up Sections of Lumber, of which the following is a full, clear, and exact description.

10 My invention relates to machines for jointing and setting up sections of lumber, and more particularly to machines for jointing and setting up sections of lumber for making box-shooks and similar purposes where sets 15 or superficies are made up of jointed sections.

My invention further relates to a machine in which the sawed sections of lumber, sawed to length and width, are automatically fed into the machine in sets, jointed upon their 20 abutting edges, and then set up ready for use.

Furthermore, my present invention is an adaptation of and improvement upon my former invention upon which I made application for Letters Patent of the United States, 25 filed February 26, 1900, Serial No. 6,523.

Referring to the drawings herewith consisting of four sheets, in which like characters of reference refer to like parts, Figures 1 and 2 30 taken together constitute a longitudinal elevation of my invention, the vertical broken lines indicating the line of union between the two sheets. Figs. 3 and 4 taken together constitute a plan view of the same, the trans- 35 verse broken lines indicating the line of union between the two sheets.

In the following description I will indicate, first, the principal features of my invention; second, the method of operation, and, third, 40 the detail mechanism.

A is the bed of the machine, which is supported upon pillars B.

C is the bed of the hopper attachment, which rests upon supports D, the supports 45 adjacent to the end of the bed A being rigidly secured to the pillar B.

E is a traveling bed which travels upon ways upon the bed A and which is made up of pivoted sections, making it an endless 50 chain. The inner faces of these sections are

provided with teeth or lugs, as shown in E', to engage with the sprockets, as hereinafter described.

F and F' are sprockets mounted upon shafts F² and F³, respectively jointed to the frame 55 and the machine. These sprockets carry the traveling bed E.

G is a pulley mounted upon a shaft G', journaled in the frame and the machine, which, through the pinion G² and a spur-gear G³, 60 transmits power to the sprocket F, which actuates the bed E. The bed E therefore transmits motion to the sprocket F'.

The shaft F³ carries a gear F⁴, which, through a gear F⁵, gives motion to a gear H', mounted 65 upon a shaft H. The shaft H carries a series of sprockets I, (see Fig. 3,) which carry sprocket-chains J, engaging with the sprockets I upon the shaft H and with sprockets K' upon the shaft K. 70

L is a hopper mounted upon the bed C, which retains the stacks of lumber-sections and which is provided at its end adjacent to the machine proper with an adjustable end, as shown at L', to regulate the width of the 75 transverse slot through which the lumber-sections find egress, as hereinafter more fully described.

M is a series of reciprocating tread-rollers which hold the lumber down firmly upon the 80 bed E.

N is a series of tread-rollers which hold the sections firmly in place while in process of being jointed upon the one side.

O is a series of set-overs which bring the 85 sections in line for jointing.

P is a series of jointers which joint the sections upon the one side.

Q is a series of reciprocating tread-rollers which hold the sections in place in progress 90 toward the second set of jointers.

R is a series of set-overs which bring the edges of the sections in line for the second set of jointers.

S is a series of jointers which joint the sections upon the opposite edges.

T is a series of tread-rollers which hold the sections firmly in place while being jointed and, which deliver the sections to the setting-up mechanism.

U and U' represent the setting-up mechanism, which consists of heavy springs U and U', which operate as hereinafter described.

Second, the method of operation: In the drawings I have shown a machine constructed for jointing and setting up four sections to form a shook or superficies. The sections of lumber, sawed to length and width, are stacked in the hopper L, the bottom set resting upon the bed C. The lugs J' upon the sprocket-chains J strike the ends of the bottom set and drive the bottom set forward onto the bed E and under the tread-roller M. The tread-rollers M rise at the proper time, and the set-overs O bring the edges of the sections to be jointed on the one side in line with the jointers P. Thus alined the rollers M grip the sections again and hold them in line while they are carried under and held by the tread-rollers N. Thereupon the jointers P joint the sections upon the first edges. The sections thus jointed on the one edge are carried forward by the bed E under the reciprocating tread-rollers Q, and then are set over and alined for jointing upon the second or opposite edges by the set-overs R. Thence carried forward under the rollers Q and under the tread-rollers T the sections are jointed by the jointers S. Thus jointed the set of sections is carried forward until it rests upon an extension of the bed, as shown at V. The next incoming set of sections will strike the ends of the section resting upon the bed V and will drive that set forward. The ends of the two interior sections will be pinched together by the springs U pressing upon their outer edges and by a shear motion will be set up in joint. The springs U' will engage the two outer sections and by a similar shear action will set up in joint the two interior sections with the two outer sections.

It is evident that the number of sections to be jointed and set in a set is a matter of mechanical construction and adaptation involving no departure from the nature of my invention.

Third, the detail mechanism: The traveling bed E, as above described, is made up of sections pivoted or hinged together to form an endless chain and is driven forward by the sprockets F engaging with the teeth E'. It is evident that in traveling over the bed A it will form a perfectly horizontal and continuously-traveling surface. These sections are routed transversely to a sufficient depth to constitute a series of longitudinal recesses to permit of the necessary drop of the cutter-heads of the jointers P and S. These recesses are indicated at E² in Figs. 3 and 4.

60 The feeding mechanism needs only the further description that the delivery of sections will be synchronized to the action of the jointing mechanism. Hence the necessity of a positive delivery such as shown. It is also evident that instead of the gearing and chains shown I may employ reciprocating shovers, for example, to deliver the sections in sets.

Referring now to the tread-rollers M, I have shown a construction identical with that shown and claimed in my said former application, Serial No. 6,523, and the tread-rollers Q are identical in construction with M. The rollers M have upwardly-projecting stems M', which pass through cross-heads M², which are secured to studs M³, secured to the frame carrying said rollers. A helical spring is interposed between said cross-head M² and the bearing-block of said rollers to force the rollers down, giving a continuous tread upon the lumber passing underneath them; but it is at once evident that in order that the set-overs O may operate the rollers M must be raised bodily out of contact with the board or strip traveling under them. A frame-support A', supported by brackets A², secured to the bed A, carries an internal cage which supports the bearing-blocks of the rollers M. Mounted upon the frame A' are brackets M⁴, in which are pivoted bell-crank levers M⁵, the upper members of which are connected by rods M⁶. The lower members connect with rods M⁷, which are pivoted to the cage carrying the blocks of the rollers M. By the action of these levers the entire frame or cage, carrying with it the rollers, is raised, freeing the rollers from contact with the lumber.

Referring especially of Fig. 3, F⁸ is a disk mounted rigidly upon the shaft F⁹, which is provided with a lug F¹¹. Pivoted to the frame of the machine is a lever-arm F⁶, the lower end of which is actuated or tripped by the lug F¹¹. This lever F⁶ connects with a pivoted lever-arm F⁷, which passes transversely under the machine and trips the valve of an air-cylinder M⁸. The piston of the air-cylinder M⁸ is connected in the usual manner with a bell-crank lever M⁵. It will thus be understood that the reciprocating action of the tread-rollers is actuated and timed by the rotation of the shaft F⁹.

110 The series of tread-rollers N and T have the same construction, with the exception that they are not made reciprocating.

The jointers P consist of cutter-heads of the ordinary type used in matching lumber. The heads depend over the traveling bed E and into the longitudinal grooves E² in order to have free access to the edges of the lumber-sections. The jointers are mounted upon vertical shafts journaled in hangers bracketed to the frame A' and are belt-driven in the ordinary manner.

115 The set-overs O and R are of identical construction arranged on opposite sides of the machine and are substantially identical in mechanism with the set-overs shown in my said former application, Serial No. 6,523. Referring now to the set-overs O, (clearly shown in Fig. 3,) O' represents transverse rods which support the cross-heads O², which carry the shovers O³. The cross-heads O² are connected with the rod O⁴, which is an extension of the piston of the air-cylinder O⁵. The cylinder O⁵ is actuated by means of a lever F⁹, identi-

cal in construction with the lever F^6 and actuated by the lug F^{11} . The lever F^9 connects with a connecting-rod F^{10} at its upper end, which actuates a trip upon the air-cylinder 5 O^5 . Thus it will be seen that the set-over is actuated by and timed to the rotation of the shaft F^8 . By this construction I am able to joint a plurality of sections at the same time, advance them through the machine with equal 10 step, and present them to the setting-up device in plane and line.

The setting-up mechanism consists of two equally-curved springs U , which are securely fastened to lugs upon the bed V . The action 15 of these springs is horizontal and inward, engaging the outer edges of the two inner sections and forcing them into joint by a shear action. The curved springs U' are similarly constructed and act upon the two outer sections in like manner.

Having thus described my invention and its method of operation, what I claim is—

1. A jointing-machine consisting of a traveling bed, a plurality of reciprocating tread-rollers, a plurality of set-overs, and a plurality 25 of jointers for jointing the sections of a set of lumber-sections upon the one edge, reciprocating tread-rollers, set-overs and jointers of like construction for jointing the sections of a set of sections of lumber upon the other edge, and means for actuating said several mechanisms substantially as and for the purposes set forth.

2. A jointing and setting-up machine, consisting of a traveling bed, a plurality of reciprocating tread-rollers a plurality of set-overs, and a plurality of jointers, for jointing the sections of a set of lumber-sections upon the one edge, reciprocating tread-rollers, set-overs, and jointers of like construction for jointing the sections of a set of lumber-sections upon the other edge, means for actuating said several mechanisms, and a setting-up device consisting of a bed, and springs 45 secured thereto and acting inwardly in pairs to set up in joint the lumber-sections, substantially as and for the purposes set forth.

3. A jointing and setting-up machine, consisting of a traveling bed, a hopper and feeding mechanism for feeding the sets of sections of lumber forward onto the traveling bed, a plurality of reciprocating tread-rollers, a plurality of set-overs, a plurality of jointers and a second series of tread-rollers, set-overs and 55 jointers for jointing the opposite edges of the sections of the sets of lumber simultaneously and means for setting up the sections of a set of lumber as fed forward from the traveling bed, means for actuating said several mechanisms, which are coördinate to each other in time and sequence, substantially as and for the purposes set forth.

4. A jointing and setting-up machine; consisting of a continuously-traveling bed and 65 an intermittent feeding mechanism, a series of tread-rollers for holding the sections in place while being jointed on the one side and

a set of set-overs for setting up the sections for such purposes, and a second set of tread-rollers for like purpose, and jointers for successively jointing the opposite edges of the sets of lumber, and setting-up mechanism for setting up the sections in sets by a shear action and mechanism for actuating said several mechanisms in time and sequence substantially as and for the purposes set forth. 70 75

5. A jointing and setting-up machine, for jointing and setting up lumber in sets of sections consisting of a continuously-traveling bed, two series of jointers having continuous motion in rotation, two series of reciprocating tread-rollers, two series of set-overs and two series of yielding non-reciprocating tread-rollers, in combination with a feeding device coördinated in action to the action of the reciprocating rollers and a setting-up mechanism consisting of curved springs secured in pairs to the auxiliary bed of the machine and acting inwardly upon the sections of the set as shoved forward and pushing them into joint by a shear action substantially as and for the purposes set forth. 80 85

6. In combination with a jointing-machine, a setting-up mechanism consisting of a bed in place with the traveling bed of the jointing-machine, and a series of springs secured to said bed at their outer ends and curved inwardly, and arranged in pairs to fence in and joint the sections by a shear action as the lumber is driven forward, substantially as 90 95 and for the purposes set forth.

7. The combination of a feeding mechanism actuated by and timed to the jointing-machine, consisting of a plurality of continuously-traveling chains provided with lugs for engaging the ends of the lumber-sections and a hopper for holding the lumber and permitting egress of the bottom set of sections only, with a jointing-machine provided with a continuously-traveling bed, a plurality of continuously-rotating jointers arranged in sets for jointing the lumber-sections on opposite sides successively, a plurality of set-overs for bringing the lumber to place, means for actuating the same governed in time by the progress of said traveling bed, a plurality of sets of tread-rollers and means for reciprocating the same timed to the action of said set-overs, and a duplicate set of set-overs and tread-rollers substantially as and for the purposes set forth. 105 110 115

8. The combination of a feeding mechanism actuated by and timed to the jointing-machine, consisting of a plurality of continuously-traveling chains provided with lugs for engaging the ends of the lumber-sections and a hopper for holding the lumber and permitting egress of the bottom set of sections only, with a jointing-machine provided with a continuously-traveling bed, a plurality of continuously-rotating jointers arranged in sets for jointing the lumber-sections on opposite sides successively, a plurality of set-overs for bringing the lumber to place, means for 120 125 130

actuating the same governed in time by the progress of said traveling bed, a plurality of sets of tread-rollers and means for reciprocating the same timed to the action of said 5 set-overs, and a duplicate set of set-overs and tread-rollers in combination with a setting-up mechanism consisting of a bed in plane with said traveling bed and inwardly-acting springs in pairs for setting up the sections by

a shear action, substantially as and for the 10 purposes set forth.

In witness whereof I have hereunto set my hand in the presence of two witnesses.

WILLIAM A. FIRSTBROOK.
